O. S. PENN

ENDLESS TRACK FOR VEHICLES

Filed March 6, 1925

INVENTOR:

OSCAR STYLES PENN,
By his Attorneys,

Baron Night

UNITED STATES PATENT OFFICE.

OSCAR STYLES PENN, OF LONDON, ENGLAND, ASSIGNOR TO ROADLESS TRACTION LIMITED, OF HOUNSLAW, ENGLAND.

ENDLESS TRACK FOR VEHICLES.

Application filed March 6, 1925. Serial No. 13,611.

To all whom it may concern:

Be it known that I, OSCAR STYLES PENN, a subject of the King of Great Britain, residing at 59 West Side, Wandsworth Common, London, England, have invented new and useful Improvements in Endless Tracks for Vehicles, of which the following is a specification.

This invention relates to endless tracks for whole or part track vehicles and the preferred type of track to which the invention is applied consists of track shoes which are connected together by links having male and female ends coupled together by a pin and in which limited universal movement is allowed between adjacent links and also in which the links are so formed that spaces are provided for the reception of lubricant and in this preferred form the teeth by which the track is driven may be centrally arranged at the top of the links.

According to this invention the paths upon which the weight carrying rollers run are arranged on each side of the teeth and above the joint pins. The joint pins are extended on each side of the joint and pass through holes in lugs carried near the edges of one link and also preferably extend beyond these lugs into holes in lugs on the adjacent link, the diameters of the first mentioned holes being greater than the diameters of the parts of the pin passing through them to allow of movement between adjacent links.

According to this invention also the track shoes may be carried by the joint pins, the shoes being secured to or made in one piece with the frame having two bearings through which the pin passes. The angle through which a shoe can turn relatively to its pin is limited by the formation of the underside of the link and the shoes may carry cushions which engage with the underside of the links. In this case the paths for the weight carrying rollers are carried by the links and form bridges between the rocking shoes.

The accompanying drawings illustrate endless tracks made in accordance with this invention. Figure 1 is a plan partly in section of three links assembled together. Figure 2 is a longitudinal section and Figure 3 is a transverse section of a link. Figure 4 is a transverse section of a link joint as in Figure 1 in which the track shoe is

carried by the joint pin and Figure 5 is a similar view in Figure 2 showing the track shoe as in Figure 4.

a are the links having paths *b* arranged on each side of the teeth *c* above the joint pins *d*. On each joint pin *d* is a bush *e* having a spherical portion housed in a spherical seating *f*, in the male end *g* of the link. *h* are housing rings provided to prevent the entrance of dirt. The joint pins *d* pass through holes in lugs *j* on the same end of the link carrying the male end *g* and also into holes in lugs *k* on the adjacent link, the diameters of the holes in the lugs *j* being greater than the diameters of the parts of the pins passing through them to allow of movement between adjacent links.

In some cases the lugs *k* may be dispensed with, the pins *d* being made shorter than shown in the drawings. The links *a* are hollow to form a reservoir for lubricant which passes to the pins *d* through holes *l*.

Referring especially to Figures 4 and 5, the track shoes *m* are secured to frames *n* having two bearings *o* through which the pin *d* passes. The angle through which the shoe can turn is limited by cushions *p* which engage with the underside of the links; the cushions *p* may be carried on the track shoes *m* as shown or upon the links. The paths *b* for the weight carrying rollers form in this case bridges between the rocking track shoes *m*.

What I claim is:—

1. A link joint comprising a pin connecting together the adjacent link ends, each link having a central lug on one end, a spherical seating in the lug, a spherical member supported by the pin and adapted to turn in the seating, two other lugs on the same end, two lugs on the other end intermediate the lugs on the first mentioned end, and holes adapted to receive the pin in all the lugs, the diameters of the holes in the first mentioned two lugs being greater than the diameters of the parts of the pin passing through them.

2. A link joint comprising a pin connecting together the adjacent link ends, each link having a central lug on one end, a spherical seating in the lug, a spherical member supported by the pin and adapted to turn in the seating, two other lugs on the same end, four lugs on the other end

intermediate the lugs on the first mentioned end, and holes adapted to receive the pin in all the lugs, the diameters of the holes in the first mentioned two lugs being greater than the diameters of the parts of the pin passing through them.

3. A link joint comprising a pin connecting together the adjacent link ends, each link having a central lug on one end, a spherical seating in the lug, a spherical member supported by the pin and adapted to turn in the seating, two other lugs on the same end, two lugs on the other end intermediate the lugs on the first mentioned end, holes adapted to receive the pin in all the lugs, the diameters of the holes in the first mentioned two lugs being greater than the diameters of the parts of the pin passing through them, a tooth on the upper part of the link and paths for the weight carrying rollers on each side of the tooth and above the pin.

4. A link joint comprising a pin connecting together the adjacent link ends, each link having a central lug on one end, a spherical seating in the lug, a spherical member supported by the pin and adapted to turn in the seating, two other lugs on the same end, four lugs on the other end intermediate the lugs on the first mentioned end, holes adapted to receive the pin in all the lugs, the diameters of the holes in the two lugs being greater than the diameters of the parts of the pin passing through them, a tooth on the upper part of the link and paths for the weight carrying rollers on each side of the tooth and above the pin.

5. A link joint comprising a pin connecting together the adjacent link ends, each link having a central lug on one end, a spherical

seating in the lug, a spherical member supported by the pin and adapted to turn in the seating, two other lugs on the same end, two lugs on the other end intermediate the lugs on the first mentioned end, holes adapted to receive the pin in all the lugs, the diameters of the holes in the first mentioned two lugs being greater than the diameters of the parts of the pin passing through them, and track shoes carried by the pins.

6. A link joint comprising a pin connecting together the adjacent link ends, each link having a central lug on one end, a spherical seating in the lug, a spherical member supported by the pin and adapted to turn in the seating, two other lugs on the same end, four lugs on the other end intermediate the lugs on the first mentioned end, holes adapted to receive the pin in all the lugs, the diameters of the holes in the two lugs being greater than the diameters of the parts of the pin passing through them, and track shoes carried by the pins.

7. A link joint comprising a pin connecting together the adjacent link ends, each link having a central lug on one end, a spherical seating in the lug, a bush with a spherical portion adapted to turn in the seating, two other lugs on the same end, two lugs on the other end intermediate the lugs on the first mentioned end, and holes in the bush and lugs through which the pin passes, the diameters of the holes in the lugs of the first mentioned end being greater than the diameters of the parts of the pin passing through them.

In testimony that I claim the foregoing as my invention I have signed my name this 12 day of February 1925.

OSCAR STYLES PENN
